CLAIM
The ornamental design for a holder for dispenser element and candle platform for holding a candle, as shown and described.

DESCRIPTION

FIG. 1 is an upper frontal perspective view of a holder for dispenser element and candle showing our new design; FIG. 2 is a front elevational, and also a rear elevational, view thereof;

FIG. 3 is a right side elevational, and also left side elevational, view thereof;

FIG. 4 is a top plan view thereof; and,

FIG. 5 is a bottom plan view thereof.

The broken lines shown in the drawings are for the purpose of illustrating portions of the article that form no part of the claimed design.

In a preferred embodiment the holder is useful in connection with supporting and/or housing a candle in a manner that facilitates the dispensing of an air treatment chemical, such as an insect repellent, from a substrate bearing the chemical.
